FIG. 5

UNITED STATES PATENT OFFICE

2,028,868

JACK

Joaquim S. Jardim, New York, N. Y.

Application September 21, 1935, Serial No. 41,586

9 Claims. (Cl. 254—88)

This invention relates to lifting devices or jacks and has for one of its objects the provision of such a device which may be operated for supporting an automobile or other vehicle in raised position, by the vehicle wheels.

Another object of the invention is the provision of a device of this character having a ramp upon which a wheel of the vehicle may ride up to actuate an obstruction which automatically releases a spring pressed plunger to support the said vehicle with one or more of its wheels above the ground.

A further object of the invention is to provide means for resetting the vehicle supporting plunger to normal lowered position to permit the vehicle to ride off therefrom.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawings, in which

Figure 1 is a side view in elevation partly in section of my improved jack;

Figure 2 is a top plan view thereof;

Figure 3 is a sectional view taken on line 3—3 of Figure 1;

Figure 4 is a top plan view of the lower section of the ramp;

Figure 5 is an end view looking from the left of Figure 1;

Figure 6 is a top plan view partly in section of the latching means for maintaining the plunger in upper position;

Figure 7 is a fragmental sectional view of a modified form of the invention, and

Figure 8 is a sectional view thereof taken on line 8—8, Figure 7.

Referring now to the drawings in detail, 10 indicates a base provided with a central longitudinally extending slideway 11 the rear end of which is closed by a block 12. A carriage shell or casing 13 comprising sections 14 and 15 respectively are suitably secured together and may be provided with balls 16 upon which the said shell may be slid into required position.

A vehicle supporting member or plunger 17 is slidably mounted in the shell and is held in its normal lowered position by releasable latch means 18 (Figs. 1 and 5). The said means comprises a finger 19 rotatably or swingably mounted in the frame 13 and normally engages a second finger 20 extending from a hub 21 mounted or secured to the forward end of a pin 22 which at its rear end is provided with an extension or pin 23 which extends into an opening 24 at the lower left side edge of the plunger. The two fingers 19 and 20 are normally held in engagement by a spring 25 on the pin 22 and the extension or pin 23 prevents the pin 22 from coming out the casing 13 when the fingers are unlatched and the spring urges the pin 22 forwardly in the direction of the arrow 26 at which time the said extension engages the end wall 27 of a recess 28 in the casing 13.

The forward end of the base 10 is provided with an opening 30 through which extends a rod 31 which also passes through the lower section 32 of a wedge or ramp 33 having an upper ramp section 34 hingedly connected thereto at 35. The lower ramp section 32 is provided at its upper surface with serrations or grooves 36 for the reception of a rod 37 which is slidably mounted on a frame 38. The above arrangement provides means for adjusting the ramp 33, as by moving the pin or rod 37 downwardly on the frame 38 so as to engage the lower or front grooves 36 the ramp opens up on its hinges thus raising anything resting thereon.

To remove a tire or wheel from a vehicle the said vehicle is driven forwardly with one of its wheels 40 riding over the ramp 33. As the wheel reaches the dot and dash position shown in Fig. 1 it contacts and depresses a rod 41 loosely mounted in the hub 21 rocking the finger 20 in the direction of the arrow 42 (Fig. 5) and disengaging same from the finger 19 permitting the spring 25 to urge the pin 22 forwardly in the direction of the arrow 26 thus carrying the extension 23 out of engagement with the plunger 17. The said plunger is then urged upwardly by a spring 43

coiled about a rod 44 against the head 45 of which and the bottom of an opening 46 in the plunger 17 the said spring exerts a tension. Any further movement of the wheel 43 causes the vehicle to be lowered and permits a portion 47 thereof to rest upon the plunger 17. With the vehicle resting on the plunger 17 the tire or wheel may be removed and replaced. In vehicles not provided with the portion 47 or where the said portion is out of lateral alinement with the plunger 17, a lever 48 pivotally mounted at 49 on the plunger 17 may be moved into the dot and dash position Fig. 2 or any other position in which a portion of the vehicle may be made to rest thereon.

15 In order to lock the plunger in upper position, I provide same with teeth 50 which are normally in engagement with a one way latching member or pawl 51 (Fig. 1) which is pivotally mounted at 52 on a horizontal plunger 53 provided with a spring 54 to urge the member 51 into contact with the teeth 50. The said plunger 53 is provided with an extension 55 having a slot 56 through which the upper end of a lever 57 extends. The said lever is pivotally mounted at 58 and when the lower end thereof is pressed inwardly in the direction of the arrow 59 the member 51 becomes disengaged from and moves out of the path of the teeth 50 permitting the plunger 17 to be depressed. In the lower position the pin 30 22 is reset by hand and the said plunger is again latched in normal position and the vehicle is driven or rolled off the jack. A stop 60 on the pawl 51 which normally engages the enlarged portion of the horizontal plunger 53 permits rotation in upward direction only of the said pawl from the position shown thus insuring freedom of upward movement of the plunger 17 and positive support thereof when in upper position.

In Figs. 7 and 8 I have shown a modified form 40 of the invention wherein means are provided for raising the plunger 17 manually. The said means comprises a ratchet member 62 having two toothed end sections 63 in mesh with the teeth 50 of the plunger 17, and a central larger toothed 45 portion 64, the teeth of which are cut in a direction opposite to the teeth of the end sections and are engaged by a pawl 65 pivotally mounted on a bifurcated rod 66 pivoted at 67 and provided with an end 68 adapted to be engaged by a tool or 50 handle 69 for rocking the rod 66 about its pivot and cause the pawl 65 to partially rotate the ratchet on each downward actuation of the handle and thus progressively raise the rack plunger 17.

55 From the foregoing, it will be seen that I have provided a jack which may be operated for supporting a vehicle in raised position by a wheel of the said vehicle, and which may be readily reset or lowered.

60 Having described my invention, what I claim as new and desire to secure by Letters Patent is:

1. A device of the nature described, comprising a base, a casing operatively mounted on the base, a spring pressed vehicle supporting member vertically slidable in the casing, means for latching the vehicle supporting member in lowered position, an obstruction extending from the said latching means for releasing same, and a ramp operatively associated with the base for the purpose specified.

2. In a vehicle jack, a base, a ramp operatively associated with the base and upon which a vehicle wheel is adapted to ride up, a casing slidable on the base, a vehicle supporting member verti-

cally slidable in the casing, releasable latching means for maintaining the vehicle supporting member in lowered position, the said means being operable by the vehicle wheel for releasing the vehicle supporting member and a spring for raising the said member when released.

3. In a vehicle jack, a base, a ramp operatively associated with the base and upon which a vehicle wheel is adapted to ride up, a casing slidable on the base, a vehicle supporting member vertically 10 slidable in the casing, releasable latching means for maintaining the vehicle supporting member in lowered position, the said means being operable by the vehicle wheel for releasing the vehicle supporting member, a spring for raising the said 15 member when released and releasable latching means for maintaining the said supporting member in raised position.

4. In a vehicle jack, a base, a ramp operatively 20 associated with the base and upon which a vehicle wheel is adapted to ride up, a casing slidable on the base, a vehicle supporting member vertically 25 slidable in the casing, releasable latching means for maintaining the vehicle supporting member in lowered position, the said means comprising a spring pressed plunger slidable in the casing and partly extending into the vehicle supporting member, a finger carried by the plunger, a second finger normally in contact with the plunger finger, an obstruction carried by the 30 plunger extending into the path of the vehicle wheel and operable thereby when in a predetermined position to disengage the fingers to release the vehicle supporting member, and a spring for raising the said member to a predetermined 35 height.

5. In a vehicle jack, a base, a ramp operatively 40 associated with the base upon which a vehicle wheel is adapted to ride up, a casing slidable on the base, a vehicle supporting member vertically 45 slidable in the casing, releasable latching means for maintaining the vehicle supporting member in lowered position, the said means comprising a spring pressed plunger slidable in the casing and partly extending into the vehicle supporting 50 member, a finger carried by the plunger, a second finger normally in contact with the plunger finger, an obstruction carried by the plunger extending into the path of the vehicle wheel and operable thereby when in a predetermined position to disengage the fingers to release the vehicle supporting member, a spring for raising the 55 said member to a predetermined height and releasable latching means for maintaining the vehicle supporting member in raised position.

6. In a vehicle jack, a base, a ramp operatively 60 associated with the base and upon which a vehicle wheel is adapted to ride up, a casing slidable on the base, a vehicle supporting member vertically 65 slidable in the casing, releasable latching means for maintaining the vehicle supporting member in lowered position, the said means being operable by the vehicle wheel for releasing the vehicle supporting member, a spring for raising the said member when released, serrations on the vehicle supporting member, releasable latching means for maintaining the said supporting member in raised position; the said means comprising a spring pressed plunger slidable in the 70 casing, a one way pawl pivotally carried by the said plunger normally in mesh with one of the serrations, and a manually operated pivotally mounted lever in engagement with the said pawl 75

carrying plunger for disengaging same from the teeth.

7. In a vehicle jack, a base, a ramp operatively associated with the base and upon which a vehicle wheel is adapted to ride up, a casing slidable on the base, a vehicle supporting member vertically slidable in the casing, releasable latching means for maintaining the vehicle supporting member in lowered position, the said means being operable by the vehicle wheel for releasing the vehicle supporting member, a spring for raising the said member when released, serrations on the vehicle supporting member, releasable latching means for maintaining the said supporting member in raised position, a toothed wheel in mesh with the serrations on the vehicle supporting member, a second toothed wheel carried by the first mentioned toothed wheel, and means associated with the second mentioned toothed wheel for progressively actuating same to rotate the first mentioned toothed wheel to raise the vehicle supporting member.

8. In combination with a vehicle jack, a ramp upon which a vehicle wheel may ride up, the said ramp comprising a lower section, the top surface of which is provided with spaced apart lateral grooves, an upper ramp section pivotally mounted at one end of the lower ramp section, the lower surface of the upper ramp section having but a single groove in alignment with the groove furthest from the pivotal end, a frame on the lower ramp section, and a rod slidably mounted thereon for the purpose specified. 10

9. In combination with a vehicle jack, a ramp upon which a vehicle wheel may ride up, the said ramp comprising a lower section, the top surface of which is provided with spaced apart lateral grooves, an upper ramp section pivotally mounted at one end of the lower ramp section, a frame on the lower ramp section, and a rod slidably mounted thereon for the purpose specified. 15
